UNITED STATES PATENT OFFICE.

SIMON E. SCHROEDER, OF NEWTON, IOWA.

WRINGER.

Application filed November 28, 1924, Serial No. 752,603. Renewed September 26, 1927.

My invention relates to wringers.

The invention relates to a power driven wringer and has special reference to general combinations effective to produce simplicity and cheapness of construction.

The invention includes details with respect to a wringer frame wherein the ordinary top rail is wholly omitted.

The invention also includes relative arrangement of parts to facilitate the disposition of a resilient member positioned below the normal wringer rolls that are adapted to be supported within a wringer frame.

The invention also includes a quick release mechanism.

Referring to the drawings,

Fig. 1, is a side elevation of a wringer including the special features of my invention.

Fig. 2, is a side elevation partly in section showing detailed arrangement of parts of the wringer.

Fig. 3, is a right hand side end view of the wringer.

Fig. 4, is a vertical cross sectional view on the line 4—4 of Fig. 2.

Fig. 5, is a cross sectional view on the line 5—5 of Figure 2; and

Fig. 6, is a fragmentary side elevation partly in section showing a modified form of a wringer embodiment.

Referring to the drawings 10 is a base framing part and 11—12 are end framing members fixed to the frame member 10.

Framing members 10, 11 and 12 are preferably fashioned of sheet metal into the substantial rectangular form shown in the drawings, the bottom portion of framing member 10 being preferably left open, and the vertical framing members 11 and 12 being opened at their inwardly facing portions and also being opened at their top ends. 13 is a wringer roll carrying a wringer shaft as 14, the ends thereof being supported by boxing blocks 15—16 supported on framing member

10, and its extreme outer end extending through opening 17 in framing member 12 and being fashioned for a coupling connection with a power source. Blocks 15—16 are vertically slotted as at 16^a to permit lifting

the wringer rolls with the plate members and more particularly the portions 29—30 thereon entirely free from the frame when the lug and roller members are disengaged.

18 is a wringer roll having an axial shaft member 19, its ends respectively being journaled in boxing members 20—21, said box-

ing members being attached respectively to plate members 22—23, said plate members having a sliding support within the clearance way in vertical framing members 11—12 60 respectively.

Plate members 22—23 are normally free to be moved with respect to the wringer frame. However, I have provided special means for interlocking of said members with respect to said frame including crank members 24—25, fixed to rockable shaft member 26, said crank members each being provided with roller member as 27—28 adapted, in practice to be caused to engage similar lug members 29—30 on the lower ends respectively of plate members 22—23. The relative arrangement of said lugs and roller members respectively on the plates and the crank members, are such that when said rollers and lugs are in engagement, the wringer rolls 13—18 will be held in close working relation.

I have provided means to effect interlocking between the plate members 22—23 and the crank members 24—25 including the rockable shaft 26, said shaft 26 being normally supported on transversely arranged strap members 31—32, but capable of movement in guideways 33—34 respectively in the end walls of vertical framing members 11—12, also locking means including a striker arm member 35 secured to one end of rocker shaft 26 by means of a pin as 36.

I have provided means for resiliently tensioning roller member 18 which includes a spring bar 37, its outer ends adapted to be supported upon members 38—39 attached to shaft 26, and adapted to be tensioned with respect to framing member 10 and rockable shaft member 26 by means of a set screw as 40.

Inasmuch as it is required that roller shaft member 14 shall project through the end framing member 12 and ends through the plate member 23, I have provided slot way 41 in said plate member to accommodate movement of the latter under the variable spacing action between roller members 13—18 in the wringing operation.

In order to properly protect the clothing passing between the wringer rolls I have provided guard plates 42—43 which are adapted to be fixed to the end framing members by means of bolts as at 44—45—46 and 47, said guard plate being vertically channeled as at 48—49 to facilitate entry of the

wringer shafts therethrough and to permit vertical movement of the upper of said shafts.

I have also provided adjustable drain part members as 50-51 pivotally supported in connection with bolt members 44-45-46 and 47.

A proper relationing of the parts to afford a proper workable wringer would include the 10 positioning of the parts as shown in Fig. 2, wherein the wringer release has been properly positioned with the trunnions of the lower roller resting in the segmental openings of the upper ends in block members 15-16 15 and the trunnions of roll 18 being disposed in the bearings in block members 20-21 and striker arm 35 being disposed in a vertical position whereby interlocking is effected between roller members 27-28 on crank members 24-25, and lug members 29-30 on plate members 22-23, thereby effecting a 20 tensioned relation between said wringer rolls under the influence of bar spring 37.

As clothing is passed between the rollers, 25 the upper wringer roll 18 will be caused to be variably spaced from the permanently positioned wringer roll 13, through the capability of plate members 22-23 to be elevated together with rocker shaft 26 30 against the tension of said bar spring 37.

To effect a release from the tensioned relation of the wringer rolls, it is only necessary to apply force to striker arm 35, to move it a sufficient distance to cause the interlocking members on the plates and crank arm members to be disengaged, thereby, leaving plate members 22-23 free to be moved vertically and in complete release from the tensioned block members 29-30.

40 Aside from the fact of the ready capability of placement and removal of the wringer rolls from the frame and their interlock, my invention presents the maximum of simplicity of construction in the omission 45 of many parts that are found in marketed commercial wringers and particularly the wringer frame structure is rendered simple in the entire omission of what is mainly known as the top rail. To remove the rolls 50 from the frame the shaft 26 is rocked to disengage the rollers 27 and 28 from the lugs 29 and 30. This releases the connector members 22 and 23 so that they can be moved vertically. Due to the slot 41 in the connector member 23 the rolls may be moved 55 vertically a sufficient distance so that by tilting the rolls the end of the shaft 14 opposite the squared end may be cleared of the top of the frame member 11. Then by a slight side movement of the roll 13 with respect to the frame that end of the roll opposite the squared portion of the shaft 14 60 may be cleared laterally of the frame to permit the roll to be moved axially, withdrawing the same from the frame. After the re-

moval of the lower roll the top roll and connectors 22 and 23 may be lifted vertically from the frame.

In Fig. 6 I have presented a modified form of my invention but will not refer to its parts in detail as it is apparent that in all respects except as to the tensioning means for the wringer rolls, the construction is the same as that disclosed in the other figures of the drawings. In the modified 75 form I dispense with the bar spring, and instead of supporting the trunnion blocks for the lower wringer roll upon the framing member 10, I have provided coil springs as 80 (one for each trunnion block) and interposed said spring between said trunnion blocks and suitable block members on the rockable shaft. The structure does not change the functioning and operating law 85 of the wringer but simply provides a different resilient active force.

What I claim is:

1. In a wringer, in combination, a frame, a wringer roll and a spring member supported in the frame, bar members slidably 90 and removably supported in the frame, a second wringer roll, a connection between the second wringer roll and the bar members and means for releasably locking the bar members to the spring member for applying pressure to the wringer rolls.

2. In a wringer, in combination, a frame having channelled side members, a wringer roll and a spring supported in the frame, bar members slidably and detachably supported in the side members and rectilinearly removable therefrom, a second wringer roll connected with the bar members and means for releasably interlocking the bar members and the spring to effect pressure between the 10 rolls.

3. In a wringer, in combination, a frame comprising a base member and channelled side members, the side members being open at the top of the channel ways, a wringer roll supported in the frame, resilient means supported in the frame, bar members movably mounted in the channels of the side members, a second wringer roll connected to said bar members and means movably 11 mounted on the frame for engagement with the bar members to lineally move the same and to apply the tension of the spring there-to to effect pressure between the rolls.

4. In a wringer, in combination, a frame 15 provided with vertical guideways therein open at their top, a roller supported in the frame, a bar spring supported in the frame positioned below the roller, vertical bar members movably positioned in the guideway having cam members at their lower end portions, a second wringer roll connected to the bar members and a rockable member supported in the frame provided with rock-ing members for engagement with the cams 1

on the bar members to place the latter under the tension of the resilient member.

5. In a wringer, in combination, a frame including a base member and vertically disposed side members having channelled ways therein, a wringer roll supported in the frame, a resilient member supported in the frame, bar members slidably and removably supported in the channel ways, a second wringer roll connected to the bar members, a rectilinearly movable rockable member supported in the frame and means on the bar members and on the rockable member moved into locking engagement by the rocking of said rockable member.

6. In a wringer, in combination, a frame, a wringer roll supported in said frame, a spring member mounted in the frame below said wringer roll, a second wringer roll above the first named wringer roll, bar members slidably supported in the frame and connected to the second named wringer roll and means for connecting the bar members with the spring member to establish pressure between the wringer rolls.

7. A wringer comprising a frame, a wringer roll journaled therein, a pressure wringer roll slidable in the frame for co-operation with said first mentioned wringer roll, a spring in the frame below said rolls, connectors for coupling the spring and the pressure wringer roll and a quick acting means for instantly connecting and disconnecting the spring and connectors.

35 8. A wringer comprising a frame, a

wringer roll journaled therein, a spring on the frame, a pressure wringer roll slidably mounted in the frame, slidably mounted connectors for coupling the spring and the pressure wringer roll, and quick acting means for connecting said connectors with the spring.

9. In a wringer, in combination, a frame, a wringer roll in said frame, a spring bar supported in the frame below the wringer roll, bar members supported in the frame and provided with cam locking members at their lower ends, a second wringer roll connected with the bar members and means for effecting connection between the bar members and the spring comprising a movable and rockable shaft in engagement with the spring, rocker arms on said shaft each provided with a locking member engageable with the cam members on the bar members and a striking arm attached to the rock shaft.

10. In a wringer, in combination, a frame, a wringer roll therein, a spring supported therein, a rocker member on which the spring bar bears and movably supported in the frame, bar members movably carried in the frame, a roll connected with the bar members, means connected with the bar members and means on the rocker member rocked into interlocking engagement with the means on the bar member by the rocking action of the rocking member.

In testimony whereof I affix my signature.

SIMON E. SCHROEDER.
